UNITED STATES PATENT OFFICE.

SAMUEL S. ADAMS, OF HARTFORD, CONNECTICUT, ASSIGNEE TO THE SMITH-WOR-
THINGTON COMPANY, OF HARTFORD, CONNECTICUT, A CORPORATION OF CON-
NECTICUT.

RIDING-SADDLETREE.

1,111,817.

Specification of Letters Patent.

Patented Sept. 29, 1914.

Application filed April 1, 1913. Serial No. 758,156.

To all whom it may concern:

Be it known that I, SAMUEL S. ADAMS, a subject of the King of Great Britain, residing at Hartford, in the county of Hartford, 5 and State of Connecticut, have invented a new and useful Improvement in Riding-Saddletrees, of which the following is a specification.

This invention relates to the construction 10 of the tree of a riding saddle of the United States Army or McClellan type. These trees are usually made of wood.

The object of this invention is to construct a tree for a saddle of this type in 15 such manner that the use of the ordinary wooden tree may be dispensed with and a saddle provided which is sufficiently firm and rigid to properly fit the back of a horse and yet will have the necessary yielding to 20 insure an easy seat for the rider without danger of chafing the horse, or of warping, twisting, cracking and permanently losing its correct shape. This object is attained by 25 constructing the side bars of the tree of leather with pockets containing spring steel strips, these parts and the pommel and cantle being put together in such manner that the desired rigidity, durability and 30 flexibility are attained without the employment of an inflexible and hard wooden tree which is liable to warp, twist and crack.

Figure 1 of the accompanying drawings shows a central longitudinal section of a saddle tree which embodies this invention. 35 Fig. 2 is a view looking up at the under side of the tree. Fig. 3 is a view looking at the front end of the tree. Fig. 4 shows a transverse section taken on the plane indicated by the dotted line 4—4 on Fig. 1, looking in the 40 direction indicated by the arrows.

The side bars of this tree are made of an upper sheet 1 and an under sheet 2 of stiff cow-hide or similar tough leather cut to the required outline and molded and stitched to 45 the desired shape. In pockets formed by longitudinal rows of stitching 3 between these layers of leather are inserted thin flat strips of spring sheet steel 4, there being preferably two strips which extend from end 50 to end in each side bar. The leather pieces forming the side bars of the tree are stitched together along the outer edges and along the edges of the central or ridge slot 5, and between the layers along the seat of the saddle a small amount of filling material, 6,

which may be hair or pieces of scrap leather may be placed to pad out the seat to the desired outline and also provide the necessary cushioning material.

The leather side bars near the front are 60 connected by the pommel core 7, which may be in the form of a wooden bridge that arches between the side bars. In front of the pommel core it is desirable to join the side bars by means of a thin spring steel 65 pommel arch 8, the ends of which are riveted to the upper surfaces of the front ends of the leather pieces. Near the rear the side bars are connected by the cantle core 9 which is shaped to the necessary outline out 70 of wood. Back of the cantle core the ends of the side bars are joined by means of a thin spring steel cantle arch 10, the ends of which are riveted to the upper surface of the rear ends of the leather pieces. The upper sheet of leather 1 extends up over the pommel core at the front and is stitched to a pommel facing 11, and extends up over the cantle at the rear, and is stitched to a cantle facing 12. The stirrup strap loops 75 13 are fastened to the side bars on each side just back of the pommel by sheet metal strips 14. A tree built in this way with side bars of leather is always sufficiently yielding to conform to conditions of use, as the 80 configuration of the rider and size of the horse. It gives slightly with the movements when in use and thus affords comfort to the rider and to the horse and yet it is rigid enough to retain its approximate shape. 85 The reinforcing strips of spring steel in the pockets in the side bars while permitting this yielding insure a resumption of normal shape. This tree will not get out of form, for as the side bars are not constructed of 90 wood there is no tendency for it to shrink and swell or warp and split. The tree is light in weight, simple to manufacture, and consequently is cheap as well as comfortable, durable and serviceable.

100 The invention claimed is:

1. A McClellan saddle-tree having side bars constructed of stitched layers of leather with pockets containing interposed spring steel strips, a high arched wooden pommel-core joining said bars a short distance back from the front end, and a wide arched wooden cantle-core joining said bars a short distance in front of the rear end, the upper leather layers of the side bars extending 105 110

upwardly over the pommel-core and upwardly over the cantle-core.

2. A McClellan saddle-tree having side bars on each side of a central opening, said bars being formed of upper and lower plies of stiff leather with interposed spring steel strips, an arched pommel extending upwardly from and joining the side bars near the front ends, an arched cantle extending

upward from and joining the side bars near the rear ends, a sheet metal pommel arch piece joining the side bars in front of the pommel and a sheet metal cantle arch joining the side bars in back of the cantle.

SAMUEL S. ADAMS.
